UNITED STATES PATENT OFFICE.

JOHN K. CLARK, OF BUFFALO, NEW YORK, ASSIGNOR, BY DIRECT AND MESNE ASSIGNMENTS, TO MARY KIMBALL CLARK, OF SAME PLACE.

RAILWAY-TIE.

SPECIFICATION forming part of Letters Patent No. 362,608, dated May 10, 1887.

Application filed August 14, 1886. Serial No. 210,921. (No model.)

To all whom it may concern:

Be it known that I, JOHN K. CLARK, a citizen of the United States, residing at Buffalo, in the county of Erie and State of New York, have invented new and useful Improvements 5 in Railway-Ties, of which the following is a specification.

This invention has for its object to provide a novel and simple hollow metallic railway-tie 10 which will bodily yield to the pressure of the passing car-wheels and retain the ballast or foundation in position therein; to provide novel means for clamping the rail upon the tie by means of bolts, whereby the bolts and 15 clamps cannot turn and the clamps thereby prevented from accidentally disengaging the rails; to produce this character of ties at a minimum cost; to provide durability, and to avoid excessive weight.

20 The objects of my invention I accomplish by the construction and combination of devices hereinafter described and claimed, reference being made to the accompanying drawings, in which—

25 Figure 1 is a perspective view of a complete railway-tie embodying my invention and showing portions of the rails in position; Fig. 2, a longitudinal sectional view taken centrally through the tie; Fig. 3, detached perspective 30 views of the parts of one tie-head; Fig. 4, detail perspective views of one of the clamps and its clamping bolt and nut, and Fig. 5 a detail end elevation showing a modification in the form of the spring top plate of the tie heads.

35 In order to enable those skilled in the art to make and use my invention, I will now describe the same in detail, referring to the drawings, where—

40 The numerals 1 indicate the tie-heads, and 2 the connecting-bar or tie-plate. As each tie-head is alike, a description of one will suffice for both. The head comprises an arched top plate, 3, having side walls, 4, riveted or bolted, 45 as at 5, to arms 6 on the end plates, 7. These end plates are composed of flat pieces of metal bent at right angles at each end to form the arms, and their upper edges, 8, may be of the general contour of the arched top plate, but 50 terminate at a distance therefrom to provide the continuous spaces 9 at each end of the top

plate, whereby the latter can yield to the pressure exerted on the rails 10 by the wheels of the passing cars. I prefer to strike up the arched plates from sheet-steel through the medium of suitable dies and to stamp out the end plates from wrought-iron, to reduce the cost of production. After these parts are connected by riveting the ends of the side walls, 4, of the spring top plate to the arm 6 on the end 55 plates, there should be present spaces of about one-eighth of an inch (more or less) between the upper edges of the end plates and the inner surface of the arched plate. The parts so constructed constitute a hollow body, which is 60 set in the ballast of the roadway, so that the end plates serve to retain the ballast or foundation in the hollow body.

The two tie-heads so constructed are connected by a tie bar or plate, 2, which is fitted 70 into recesses 11 formed centrally in the top edges of the inner end plate of each head, the extremities of the tie-plate being bolted to the arched top plate by bolts 12, having squared portions 13 engaging corresponding openings 75 in the tie-plate and passing through round or angular bolt-holes 13^a in the top plate, 3, the nuts for securing the bolts being above the top plate, so that they can be conveniently reached for any desired purpose. The engagement of 80 the tie-plate with recesses in the inner end plates prevents the tie-plate and the heads from moving out of proper alignment.

The top plate is preferably curved where the rail rests; but obviously it may be flattened at 85 this point, as shown in Fig. 5, without changing the character of the invention. The top plate is provided with two adjacent square or angular orifices, 15, through which pass bolts 16, which are square for their entire length, except as to the upper screw-treaded ends which engage the screw-nuts 17. These bolts pass through square or angular orifices 18 in the clamps 19, each of which consists of a flat plate of metal resting at one end on the base-flange of the rail and having the other end bent or turned at right angles, or approximately so, to form a foot, 20, which rests upon the arched top plate. When the clamps are 95 pressing on the flanges of the rails, the square upper end portions of the bolts pass about one-half the distance through the square orifices 100

in the clamps, (more or less,) so that even if the screw-nuts should work loose the clamps cannot turn and disengage the rail-flanges, which is very important in this class of devices for clamping the rails to the tie.

It will be seen that all the bolt-nuts are exposed above the tie, which renders them easily accessible to the track-walkers or others whose duty it is to preserve the road in perfect order.

- 10 In case a train is derailed and tie-heads at one side seriously damaged, such tie-heads can be readily removed and perfect ones substituted therefor without disturbing the tie-heads at the opposite side of the track.
- 15 By constructing the tie-heads of separate end and top plates and uniting these parts by rivets or their equivalent the entire head will yield to the pressure of the train and be more durable than if made in a single piece.
- 20 In building a railroad according to my invention I contemplate arranging the rails so that their adjacent ends meet centrally on the tie-head, and secure such ends by the clamps, which will be made of sufficient width to span
- 25 the line of separation between the rails and bear about one and one-half inch on the flanges of each rail, thereby providing a strong connection and giving flexibility to the ends of the rail.
- 30 Having thus described my invention, what I claim is—
- 1. A rail-supporting head for a railway-tie, consisting of a yielding metallic top plate and side walls, and separately attached metallic end walls retaining the ballast or foundation, substantially as described.
- 2. A rail-supporting head for a railway-tie, consisting of the elastic metallic top plate and the separate end plates connected therewith
- 40 and having their top edges separated from the inner surfaces of the top plate, substantially as described.
- 3. A railway-tie consisting of a tie-plate and two tie-heads, each consisting of an elastic metal top plate, and two end plates riveted to

the top plate and separated therefrom at their top edges by intervening spaces, substantially as described.

4. A railway-tie consisting of a tie-plate and two tie-heads, each consisting of an elastic metal top plate having bolt-holes, the separate end plates riveted to the top plate and separated therefrom at their top edges by intervening spaces, clamps for engaging the rail-flanges, and bolts passing through the elastic top plate and the clamps, substantially as described.

5. A railway-tie consisting of a tie-plate and two tie-heads, each having square or angular bolt-holes, the clamps having square or angular bolt-holes, and the square or angular bolts whereby the clamps, when pressing on the rail-flanges, engage by their square bolt-holes with the square portion of the bolts, substantially as and for the purpose described.

6. A railway-tie consisting of a tie-plate and two tie-heads, each comprising an elastic metal top plate and end walls, separated therefrom at their top edges, and one of which is provided with a recess receiving the tie-plate, and bolts connecting the ends of the tie-plate with the elastic top plate, substantially as described.

7. The combination, in a railway-tie, of a tie-head having its top wall provided with angular bolt-holes, the clamps each consisting of a metal plate having an angular bolt-hole and bearing at one end on the rail-flanges and bent at the other end at right angles, or approximately so, to form a foot resting on the top plate, and angular bolts passing through the said bolt-holes, and with the angular portions of which the clamps engage, substantially as described.

In testimony whereof I affix my signature in presence of two witnesses.

JOHN K. CLARK.
